INDUCTION COIL

Arni Helgason, Chicago, Ill., assignor to Chicago
Transformer Corporation, a corporation of Illi-
nois

Application August 18, 1939, Serial No. 290,814

5 Claims. (Cl. 175—356)

This invention relates to induction coils and particularly to coils for high speed internal combustion engines. Due to the number of cylinders and speed of modern engines, the time for generating an ignition current is extremely small. Hence coils having low inductance must be used. To improve the efficiency of such coils it has been the custom to taper the secondary width to a minimum outer larger width and at the same time use long laminations whose ends are bent around the coil after insertion therein. Such a construction is shown in Patent 1,908,798 to Toelle.

The construction of the coil shown in this patent involves difficulties for testing. The complete coil must pass a rigid test for inductance and must perform satisfactorily, the tolerances being rather narrow.

Coils of this type are cased in a moulded housing with rather a snug fit. This case serves to press the core ends down tightly into position and the working conditions of the coil presuppose such a core condition. Hence to test a coil properly, such conditions should be duplicated.

It is desirable to test the coils prior to encasing since removal of a coil from its housing for adjustment purposes is too difficult and time consuming.

In the Toelle structure, the bending of the laminations around the coil makes the testing of such a coil difficult. Due to the spring of the metal and the lack of precision of the shaping of the steel strips, some substitute for the final housing must be used in the test if the inductance of the coil under operating conditions is to be duplicated.

In accordance with this invention, I have modified the construction of the Toelle patent so that the above difficulties are eliminated. In general, my invention contemplates pre-shaping the laminations in such a manner that variations in the reluctance of the magnetic circuit are reduced to negligible proportions. This pre-shaping or pre-forming contemplates the actual bending of the steel, and is to be distinguished from stamping laminations.

Stamping of laminations for ignition coils, that is, using flat stamped laminations, has been attempted with some success but involves some rather serious difficulties. Thus, because of the coil shape, it is impossible to stamp out one lamination whose ends would curl around the coil as shown in the Toelle patent. If the strip is divided at the coil interior, then variations in air gap become serious. In a coil of this

character, an air gap variation in the coil interior is much more critical than on the exterior of the coil. A short straight gap across the strip within the coil is therefore out of consideration. Increasing the gap length by shaping the end of the strip greatly increases steel waste in stamping.

By my invention, I am enabled to produce an ignition coil such as shown by Toelle in his patent in quantity production without in any way compromising the excellence or characteristics thereof and yet without excessive production costs.

Referring to the drawing:

Fig. 1 shows a sectional view of a coil embodying the present invention;

Fig. 2 is a detail of one of the members for clamping the laminations in position;

Fig. 3 is a detail of the other member cooperating with the member shown in Fig. 2;

Fig. 4 shows an outline view of a coil having a shaping member on the outside of the laminations; and

Fig. 5 shows a lamination.

The coil comprises a tube 10 suitably shaped of stiff insulating material upon which is wound a primary winding 11 of coarse wire. This winding may be composed of several layers of wire preferably extending the full length of the coil. Disposed over primary winding 11 and suitably insulated therefrom is a secondary winding 12 of fine wire. This secondary tapers from the bottom layer which is somewhat shorter than the primary coil up to the top or outer layer. It is understood, of course, that suitable insulation is provided. The entire coil may then be wrapped with suitable insulating material 15.

Within insulating tube 10 are disposed four groups of laminations numbered 16 to 19 inclusive. The various groups of laminations are all similar so that only one need be described in detail. Thus, referring to group 16, this group is composed of a number of laminations having a long straight portion 20 and a curved portion 21 adapted to overlie the end of the coil and terminating in a tip 22. Each of these laminations is made of suitable steel and shaped so that the group nest as shown. The shaping of the laminations may be accomplished in any suitable manner such as by bending a single lamination or group of laminations over a suitable metal plate.

In the bending of the lamination groups, it is preferred to make a sharp right angle 23 in the innermost lamination 24 of each group and shape the remaining strips accordingly. In this way, 55

the free end of straight portion 20 of each group can extend right up to the abutting lamination. In this connection it should be observed that the straight portions 20 of the laminations should be aligned at their free ends so that any possible air gap variation be reduced to a minimum.

As clearly shown in Fig. 1 the laminations for each group are disposed adjacent to each other to form a compact unit. Group 17 of the laminations has its long portion 20 disposed adjacent to the corresponding portion of group 16. Groups 18 and 19 are disposed in corresponding relation to each other in a manner similar to groups 16 and 17.

15 In order to maintain the entire transformer intact, suitable clamp means is provided. Thus as shown in Figs. 2 and 3, a sheet metal member of a general T-shape is provided. This metal member has a body 25 having its end 26 split at 27. The head is provided with a cross-member 28 whose sides 29 are bent over to form flanges. The head 28 is in the shape shown so that the entire member may be stamped out of a single piece of metal. The width of head 28 is equal to 25 the width of each lamination and the sides 29 are adapted to lie along the edges of each group of laminations.

Member 25 is disposed preferably along the center of the space occupied by the straight portions 20 of the laminations and extends the full length of the coil. Cooperating with portion 25 is a small U-shaped member 30 whose sides 31 are flanged in a manner similar to that of head 28. Member 30 is provided with a slot 32 transversely thereof into which end 26 of member 25 is adapted to fit. The end 26 passes through the slot and the two portions opposite slit 27 are then bent on opposite sides to lock the entire assembly.

40 If desired, heavy retaining members 35 and 36 suitably shaped may be disposed over each end of the coil to fit over the end group of laminations. In this way, an iron clad construction is provided.

45 What is claimed is:

1. An induction coil comprising a straight primary winding, a secondary winding superposed and concentric with said primary winding, said secondary winding consisting of a plurality of 50 layers of wire with the layer adjacent the primary having the greatest number of turns and with the succeeding layers having less turns, and a magnetizing core, said magnetizing core comprising preformed and preshaped laminations divided into four groups, each group of laminations 55 consisting of nested individual laminations having one end portion straight and disposed within the interior of said windings and extending the full coil length and the other end portion bent 60 along lines parallel to the width of the strip and following the coil around the end and outer surface toward the middle part of the coil, two groups extending from one coil end but bent away from each other along the coil end, the 65 remaining two groups extending from the other

coil end and bent away from each other, one group of the first-mentioned two groups and one group of the second mentioned two groups having the portions on the outer coil surface extending toward each other and forming an air gap at 5 the middle part of the coil, the remaining groups forming a similar air gap on the outer coil surface on the other side of the coil and means for maintaining said laminations on said coil whereby there results an ignition coil having a 10 small time constant and high efficiency and whose inductance may be closely controlled in production.

2. The induction coil of claim 1 wherein said means for maintaining said laminations consists 15 of a clamping means engaging said laminations at opposite ends of said coil.

3. The structure of claim 1 wherein said means for maintaining said laminations consists of a heavy strip of metal extending along the outside 20 of two groups of laminations at one end of the coil and a similar strip along the outside of the other two groups and means for maintaining said strips rigidly in position.

4. An induction coil comprising an elongated 25 primary winding, a secondary winding disposed in concentric relation to the primary with said secondary winding consisting of a plurality of 30 layers of wire tapering symmetrically with respect to said primary from a bottom layer having the greatest number of turns to a top layer having the smallest number of turns, and a laminated preformed preshaped magnetizing core for 35 said coil, said core consisting of four groups of laminations, each group consisting of a plurality 40 of flat preshaped nested laminations with an end portion of each lamination being straight and disposed within the interior of said coil and extending the full coil length and the other end portion being curved along lines parallel to the width thereof and following the coil around the end and outer surface toward the middle part of the coil, two groups extending from one coil end but bent away from each other along the coil end, the remaining two groups extending from the other 45 coil end and bent away from each other, one group of the first-mentioned two groups and one group of the second mentioned two groups having the portions on the outer coil surface extending toward each other and forming an air 50 gap at the middle part of the coil, the remaining groups forming a similar air gap on the outer coil surface on the other side of the coil and means for maintaining said groups rigidly in position whereby there results an ignition coil having a 55 small time constant and high efficiency and whose inductance may be closely controlled in production.

5. The structure of claim 4 wherein said last-named means consists of an I-shaped structure 60 with the end pieces extending along the laminations at the coil ends and the connecting strip extending between the lamination groups along the coil interior.
